UNITED STATES PATENT OFFICE.

JOSEPH L. CHAPMAN, OF HADDONFIELD, NEW JERSEY.

AUTOMATIC STOP-VALVE.

SPECIFICATION forming part of Letters Patent No. 334,640, dated January 19, 1886.

Application filed May 12, 1885. Serial No. 165,161. (No model.)

To all whom it may concern:

Be it known that I, JOSEPH L. CHAPMAN, of Haddonfield, in the county of Camden and State of New Jersey, have invented a new and 5 valuable Improvement in Automatic Stop-Valves; and I do hereby declare that the following is a full, clear, and exact description of the construction and operation of the same, reference being had to the annexed drawings, 10 making a part of this specification, and to the letters and figures of reference marked thereon.

Figure 1 is a longitudinal vertical section of a stop or cut-off for gas embodying my improvement. Fig. 2 is an inverted plan, partly 15 sectional, on line 1 1, Fig. 1. Fig. 3 is a side elevation; Fig. 4, a plan; and Fig. 5 is an enlarged sectional plan of a portion of the diaphragm and rod attachment secured thereto.

My invention has relation to automatic stop 20 or cut-offs for preventing natural or other gases entering the supply or burner pipes after the flow has stopped; and it has for its object simplicity and durability of construction.

My invention, accordingly, consists of the 25 combination, construction, and arrangement of parts, as hereinafter more particularly described and claimed.

In the drawings, A represents the stop or 30 cut-off casing, which is oblong in shape and is composed of hollow upper and lower sections, B and C, respectively, forming an inner chamber, A', and each of which is provided with side lugs, b and c, through which pass fastening-bolts D, to provide for detaching one casing-section from the other for repairs or other purposes. The meeting-edges of these sections are trued or finished to provide a true or light joint between them, and, if desired, any suitable packing or red lead may be used to further insure a sealed joint between said sections.

The upper section, B, has at one end a chamber, E, in one end of which is an inlet-opening, e. It is also provided with a bottom opening, e', and a top opening, e''. The upper edge, e', of bottom opening, e', forms a seat, e'', for a valve, f, having a stem, F, the upper end, f', of which enters and works in a tubular nipple or plug, G, screwed into top opening, e'', of chamber E. The lower end, f'', of said valve-stem F 45 is secured to end h of a lever, H, which, at its opposite end, h', is pivoted to lugs h'', formed

on the bottom side of an outlet opening, b', on section B. The outlet-opening b' of section B is preferably located on a side or end opposite that in which is formed the inlet-opening e. 55 The top of section B is provided with an enlarged aperture, I, to form which the sides of said section are built out, as shown at b'', and upon which rests a cap or cover, K, screwed or fastened to section B by bolts k; or other 60 suitable fastenings may be provided, as desired, and, if desired, said cap is provided with a vent-pipe, k'. Between said cover and section B is interposed a flexible diaphragm, L, and the top of the cover is formed with an externally-threaded projection, k'', having opening k''. Upon projection k'' screws a cap, M, which incloses an upper or handle end, n, of a rod, N, passing down through opening k'' and screwing into the top of a stem, l, fastened to 70 the center of the diaphragm L, as shown more plainly in Fig. 5. The lower end of the diaphragm stem l is loosely jointed to the lever H, as shown, so that a manual movement of the rod N, when cap M is unscrewed, raises diaphragm L and lever H to open valve f and admit a flow of gas to and through chamber A'. 75

As soon as the valve f is raised, the cap M is returned to its place or screwed upon projection k'', and the pressure of the gas in the 80 cut-off chamber A' maintains the diaphragm in an elevated position to keep valve f open as long as the gas continues to flow to and through the cut-off. When, however, the gas stops flowing into inlet-opening e, the lever H 85 and diaphragm L drop to automatically close valve f to cut off admission to chamber A'.

I have shown the cap or cover K and the diaphragm L located in the center of the cut-off casing; but, as it obviously may be otherwise located, I do not confine myself to the location shown.

What I claim is—

1. The combination casing-section B C, having lugs b c and fastening-bolts D, the diaphragm L, having stem l and lifting-rod N, cap K, chamber E, having inlet and outlet openings e e', and valve f, having stem F, and lever H, pivoted to one of said sections and having connection with said diaphragm and valve-stems, substantially as shown and described. 95

2. The combination of casing-sections B C, having fastening-bolts D, the diaphragm L, having stem l and rod N, chamber E, having inlet and outlet openings e e', valve F, having stem f, and lever H, pivoted to one of said sections and having connection with said diaphragm and valve, substantially as shown, and for the purpose set forth.

In testimony that I claim the above I have hereunto subscribed my name in the presence of two witnesses.

JOSEPH L. CHAPMAN.
